(57) **CLAIM**

The ornamental design for a lighting control console, as shown and described.

DESCRIPTION

FIG. 1 is a right, top, front perspective view of a lighting control console embodying my new design in a first position;

FIG. 2 is a front view thereof;

FIG. 3 is a top view thereof;

FIG. 4 is a left side view thereof;

FIG. 5 is a right side view thereof;

FIG. 6 is a right side view thereof in a second position; and, FIG. 7 is a right, top, front perspective view thereof in a third position.

The presentations show the device whose design is claimed in different use phases and the respective alternating positions. The unillustrated rear and bottom portions of the lighting control console in the first position form no part of the claimed design.
